(57) **CLAIM**

I claim the ornamental design for a rectangle container, as shown, and described.

DESCRIPTION

FIG. 1 is a perspective view of a rectangle container showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof; and

FIG. 7 is a bottom plan view thereof; and,

FIG. 8 is an enlarged cross sectional view of a portion of FIG. 6.

1 Claim, 8 Drawing Sheets

FIG. 1

FIG. 2

FIG. 3

FIG. 4

FIG. 5

FIG. 6
